GARMENT FASTENERS

John L. Cadley, Milford, Conn., assignor to
Air-Lock, Inc., Milford, Conn.
Filed May 12, 1960, Ser. No. 28,730
2 Claims. (Cl. 24—230)

My invention relates to garment fasteners and in particular to snap fasteners for brassieres and the like, which may be released by finger pressure, instead of having to be ripped apart, as is common with the usual snap fasteners now in use.

My preferred form of snap fastener consists of a socket member and a separable slide member. The socket member consists of a one-piece stamping of thin spring material having a strap slot at one end, an integral latch portion comprising a tongue having a free end facing the strap slot punched from the plane of the body and side portions folded over on each side of the forward portion of the latch to form a groove and socket to stop and limit the forward thrust of the separable slide. It is apparent that both members lend themselves to low cost, automatic production. The slide member is a flat ring stamping of sheet material having a strap slot at one end and matching the shape of the spring latch portion of the body member and adapted to depress same and drop over the free end thereof and expose the latch to finger pressure.

In operation the slide member is slipped in the grooves of the socket member only as far as permitted by the folded sides and slides over the upstanding spring latch portion, depresses it and surrounds it as it snaps up into exposed position into the matching opening of the ring, thereby preventing withdrawal of the slide until the latch is depressed. Finger pressure, depressing the latch, automatically releases the slide, as the tension on the straps separates the members.

For brassieres and other garments where a single fastener is used, my preferred shape of latch is circular and of such size as may readily be depressed by a finger. This shape permits a slide with a matching circular opening to rotate around the circular latch to a considerable degree and thus provide freedom of movement without strain on the garment. For other garments, various other shapes may be preferred, as for instance a rectangular shape as shown in the drawings.

With the foregoing and other objects in view, as will be apparent to those skilled in the art as the description proceeds, my invention resides in the combination and arrangement of parts and in the details of construction described in this specification and particularly pointed out in the appended claim, it being understood that changes may be made in the particular embodiment of the invention, within the scope of what is claimed, without departing from the spirit of the invention. I intend no limitation other than those of the claim when fairly interpreted in the light of the full disclosure and the present state of the art.

Referring now to the accompanying drawings illustrative of a preferred embodiment of my invention, FIG. 1 illustrates a blank from which a socket or body member

2

may be formed; FIG. 2 is a plan view of a socket member made from the blank of FIG. 1; FIG. 3 is a sectional view on the line A—A of FIG. 2; FIG. 4 shows a matching slide member; FIG. 5 is a sectional view similar to FIG. 3, showing the slide in position; FIG. 6 illustrates the assembly with the slide member of FIG. 4 rotated around the latch of the socket member; FIGS. 7 and 8 illustrate a modification. Similar reference characters relate to similar parts throughout the several views.

In FIG. 1 is shown a blank of thin sheet spring material from which the entire socket member 10 is formed, having an integral upsprung latch tongue portion 9, symmetrical side members 7 and 8, and a strap slot 6 punched out at the end 5 of the blank. The side members 7 and 8 are folded over the forward part of latch 9 to form a stop as shown in FIG. 2. They are spaced from the flat body of the blank a distance corresponding to the thickness of the slide material (FIG. 5) to form the grooves and socket for the reception of the ring 4, which ring has a strap slot 2 at the end 1 and an opening 3 to correspond with the shape of the latch 9. Thus when the ring slide is inserted into the groove and socket of the body member 10 (FIG. 5), it rides up over the latch 9, wedges it down, and then the latch snaps up to exposed position through the opening 3, restraining the slide 4 but permitting a degree of rotation of the slide around the latch, as illustrated in FIG. 6.

Other shapes of socket members may be formed from blanks, as shown in FIG. 7, where side members 7a and 8a are folded over to give a rectangular configuration, with a latch member 9a provided to restrain a rectangular slide (FIG. 8) having a rectangular opening 3a.

What I claim is:

1. A garment fastener comprising a one piece body member of flat, thin, spring material having a strap slot therethrough at one end, an integral latch portion up-sprung from the plane of the body member comprising a circular tongue having a free end facing said strap slot, and stop members folded over on each side of the latch portion forward thereof and spaced from said plane to form grooves for the reception of a flat slide member and a separable one piece flat ring member of a thickness substantially equal to the dimension of said spacing, having a slot at one end and adapted to depress said tongue, drop over said free end, and expose said tongue to finger pressure.

2. A fastener, as recited in claim 1, in which the latch portion of said body member and the opening in said ring member are of such matching shape and size as to permit rotation of said slide about said latch.
